COMBINATION CLOCK AND CALCULATOR

Moto Shimano, Los Angeles, and Lloyd Y. Ishimaru,
Agoura, Calif., assignors to Garrett Comtronics Cor-
poration, San Diego, Calif.

Filed June 1, 1972, Ser. No. 258,923

Term of patent 14 years

Int. Cl. D14—02

U.S. Cl. D26—5 C

FIG. 1.

FIG. 2.

FIG. 3.

FIG. 4.

FIG. 5.

FIG. 1 is a perspective view taken from the front, left side and top of a combination clock and calculator with the calculator pushbutton depressed showing our new design;

FIG. 2 is a top plan view thereof;

FIG. 3 is a right side elevational view thereof;

FIG. 4 is a rear elevational view thereof; and

FIG. 5 is a perspective view taken from the front, left side and top thereof showing the clock pushbutton depressed.

It is to be understood that the texture pattern is complete throughout the lower front panel as shown in FIGS. 1 and 5.

We claim:

The ornamental design for a combination clock and calculator, as shown and described.
